UNITED STATES PATENT OFFICE.

AUGUST ROSENTHAL, OF WEST ALLIS, WISCONSIN.

STRAW ELEVATOR AND STACKER.

1,030,015.

Specification of Letters Patent. Patented June 18, 1912.

Application filed October 16, 1908. Serial No. 458,044.

To all whom it may concern:

Be it known that I, AUGUST ROSENTHAL, residing in West Allis, in the county of Milwaukee and State of Wisconsin, have 5 invented new and useful Improvements in Straw Elevators and Stackers, of which the following is a description, reference being had to the accompanying drawings, which are a part of this specification.

10 This invention relates to improvements in straw elevators and stackers adapted for use with corn husking and shredding machines, and ensilage cutters, and has for its principal object to construct a device of this 15 character which shall possess superior advantages in point of simplicity and general efficiency.

10 A further object of the invention is to provide a stacker in which straw and fodder will be elevated and discharged from the stacker by oscillating and reciprocating means provided with engaging fingers.

20 A further object of the invention is to provide a jointed stacker tube and reciprocating means which may be folded without uncoupling any of the parts.

25 A further object of this invention is to provide a swiveled stacker which may be elevated or swung to any angle desired 30 without affecting the transmission of power to the oscillating and reciprocating means.

With the above, and other objects, in view, the invention consists of the devices and parts, or their equivalents, as hereinafter 35 set forth.

40 In the accompanying drawings, in which the same reference characters designate the same parts in all of the views: Figure 1 is a side view of a portion of a threshing machine provided with the improved elevator and stacker, parts broken away and other parts being in section; Fig. 2 is a longitudinal sectional view of the stacker; Fig. 3 45 is a transverse sectional view of the stacker taken on line 3-3 of Fig. 1; Fig. 4 is an enlarged transverse sectional view of the stacker taken on line 4-4 of Fig. 1; Fig. 5 is an enlarged plan view of the jointed portion of the stacker; Fig. 6 is an enlarged inverted plan view of a fragment of the reciprocating means; and Fig. 7 is a side view of a portion of the stacker showing one portion of the stacker tube folded upon the other.

55 Referring to the drawings, the numeral

10 indicates the discharge end of a threshing machine, and 11 the discharge spout or outlet thereof. A stacker supporting frame 12 extends rearwardly from the threshing machine and on this frame a rectangular stacker frame 13 is pivotally supported by means of a pivotal connection 14 mounted on the lower portion of said supporting frame, and a yoke 15 depends from the upper portion of the supporting frame and is 60 pivotally connected to the top of the rectangular frame.

65 A curved trough 16 is rigidly connected to the lower portion of the rectangular frame by straps 17 and extends beneath the 70 discharge end of the discharge spout 11 of the threshing machine. This trough is curved concentric, horizontally, to the pivotal connection of the rectangular frame with the supporting frame thus permitting 75 the trough to receive material from the discharge spout in any position of adjustment of the rectangular frame desired. A double cranked shaft 18 is mounted medially on the rectangular frame and a 80 stacker 19 formed of an inner section 20 and an outer discharge section 21 connected together by a hinge joint 22 is pivotally connected on said shaft.

85 A short shaft 23 mounted beneath the upper portion of the supporting frame 12 is provided with a power transmitting wheel or pulley 24 on its outer end and with a universal coupling 25 on its inner end. Another short shaft 26 mounted on the upper portion of the rectangular frame 13 is 90 connected to the universal coupling at one end and at the other end is provided with a sprocket wheel 27. The corresponding end of the double cranked shaft 18 is provided with a similar sprocket wheel 28 and a sprocket chain 29 connects the two wheels together.

95 The pivotal connections of the universal coupling connecting the inner ends of the short shafts together are positioned in vertical alignment with the pivotal bolts of the rectangular frame thus permitting the rotation of the short shafts, even though at an angle with relation to each other, and the 100 operation of the stacker in different positions of horizontal adjustment. Two oscillating bars 30 provided with both rigid and swinging depending material engaging fingers 31 and 32 respectively are connected 105 110

to the cranked portion of the double cranked shaft at their inner ends and their outer ends are pivotally and slidably mounted in channeled guides 33 forming part of the upper portion of each tube section adjacent to the hinge joint. Reciprocating bars 34 also provided with swinging engaging fingers 32 depending therefrom are pivoted to the outer ends of the oscillating bars and are 5 adapted to be reciprocated thereby. The outer ends of these reciprocating bars are supported by means of bolts 35 (only one being shown) extending through slots provided in the discharge tube section. The 10 arms 36 which serve to pivotally connect the reciprocating bars to the oscillating bars are curved so that said arm will clear the hinge pin 37 when the stacker is in the folded position as shown in Fig. 7. Pins 15 20 38 which extend laterally from the oscillating bars and serve as pivotal connections between the said arms and the channel guides are provided with anti-friction rollers 39 to reduce the sliding friction there- 25 between to the minimum. The ends of the channel guides at the joint of the tube are connected to and supported by means of cross bars 40 which extend across the stacker tube from one side to the other immediately 30 beneath the hinge pin 37.

The ends of the hinge pin 37 project beyond the ears of the hinge portion of the stacker and have mounted thereon hook members 41 and to these hook members is 35 connected a bail 42. A rope 43 connected to the bail extends toward the threshing machine and between two guide rollers 44 mounted on the supporting frame and positioned directly above the pivotal connection 40 of the rectangular frame thereto. The rope then passes around a small windlass mounted on top of the threshing machine and is the means whereby the outer end of the stacker is raised, lowered, and held in 45 an adjusted position. The guide rollers being mounted directly above the pivotal connection of the rectangular frame permits the stacker to be swung horizontally to any position desired without affecting the adjustment of the height of the stacker end. 50

The inner end 45 of the stacker is enlarged and the lower portion 46 of this enlargement is curved concentrically to the cranked shaft 18 and partly overlaps the 55 outer end of the trough 16 which is likewise curved so as to permit the stacker to swing on the shaft 18 without passing from beneath the trough. The swinging material engaging fingers are connected to the bars 60 and their movement limited by means of the shoulders 47 and 48 formed by recessing the lower side edges of the bars from said edges to the openings 49 through which the fingers pass and are pivotally connected to 65 said bars. The engaging fingers are formed

by passing rods through the openings 49 and bending said rods downwardly in the shape of an inverted U with a part of the stems of the U-shaped rods positioned within the recesses so that in swinging the stems 70 will engage the shoulders and their movement will be limited. The rigid fingers are formed in the same manner with the exception that the bars are only recessed the width of the diameter of the rods in order 75 to hold them rigidly to the bars. As the fingers connected to the inner portion of the oscillating bars are raised out of the material by the oscillating movement of said bars it is unnecessary to provide for their 80 swinging up against the bars during the return stroke and they are therefore rigidly connected to said bars.

The operation of the stacker is as follows: Material is fed to the stacker in the 85 lower curved end thereof from the discharge spout of the machine to which it is connected by means of the trough. The material will be engaged first by the rigid fingers of the oscillating bars during the 90 downward and forward stroke of each bar and then moved upwardly into the more contracted portion of the stacker tube where it will be engaged by the swinging fingers of the oscillating bars and moved 95 into the path of movement of the reciprocating bars which will further move the material and finally discharge it from the discharge end of the stacker. The swinging fingers of both the oscillating and reciprocating bars will engage the material during the forward stroke and during the return will swing up against the sides of the bars and pass freely through the advancing material. By means of the double cranked 100 shaft, the cranked portions of which are opposite with relation to each other, the bars on one side are advancing the material while the bars on the other side are retreating thus providing means for continuously 105 discharging material from the stacker. 110

The stacker may be swung around horizontally by means of the pivotal connection of the rectangular stacker frame to the supporting frame, and may be raised or lowered by means of the pivotal connection of the stacker tube to the rectangular frame and the rope and windlass. The novel arrangement of the trough permits these adjustments without interfering with the feeding of the material to the stacker tube. By means of the hinged stacker tube and the jointed bars the stacker may be folded upon itself, by turning the cranked shaft so that the joints of the bars are in alinement, for convenience in moving the machine to which the stacker is connected from place to place. 115 120 125

From the foregoing description of the construction and operation of the device it will be seen that a stacker is provided which 130

is very simple in construction and efficient in operation and contains but a minimum number of parts.

It is to be understood that this invention is not limited to any specific form or arrangement of parts except in so far as such limitations are specified in the claims.

What I claim as my invention is:

1. An elevator and stacker, comprising a tube formed of two sections hinged together and arranged to permit one section to be folded on the other section, movable bars hinged together endwise and associated with said tube and provided with fingers for moving material within the tube, and a guide positioned below the plane of the tube hinge when said tube is in horizontal position for guiding said movable bars, the hinge connection of the bars permitting said bars to be folded with the tube sections.
2. An elevator and stacker, comprising a tube formed of two sections hinged together and arranged to permit one section to be folded on the other section, movable bars associated with said tube and provided with fingers for moving material within the tube, a curved hinge connecting the ends of the bars together, and a guide positioned below the plane of the tube hinge when said tube is in horizontal position for guiding said movable bars, the curved hinge connection of the bars permitting said bars to be folded with the tube sections.
3. An elevator and stacker, comprising a tube formed of two sections hinged together, movable bars associated with said tube and provided with means for moving material within said tube, channeled guide bars positioned below the plane of the tube hinge for guiding the movable bars, a cranked shaft for moving the movable bars, and means connecting the bars together whereby said bars may be folded with the tube sections.
4. An elevator and stacker comprising a tube provided with a slot and formed of two sections hinged together at a point outside of their circumferential diameters, channeled guide bars positioned below the plane of the tube hinge, a cranked shaft adjacent to said tube, an oscillating bar provided with means for engaging material within the tube connected to said cranked shaft, a pivotal and slid able connection between one end of the oscillating bar and the channeled guide bars, a reciprocating bar associated with said tube and provided with material engaging fingers, means connected to said reciprocating bar and guided by the slot of the tube, and means connecting the bars together whereby said bars may be folded with the tube sections.
5. An elevator and stacker, comprising a tube formed of two sections hinged together at a point outside of their circumferential

diameters, guiding means positioned below the plane of the tube hinge, a cranked shaft adjacent to said tube, bars provided with means for engaging material within said tube moved by said cranked shaft, and means connecting the bars together whereby when said bars are folded with the tube sections one of said bars will be above the plane of the tube hinge.

6. An elevator and stacker, comprising a tube formed of two sections hinged together at a point outside of their circumferential diameters, guiding means positioned below the plane of the tube hinge, a cranked shaft adjacent to said tube, bars provided with means for engaging material within said tube moved by said cranked shaft, shoulders formed on said bars for limited the movement of the material engaging means, and means connecting the bars together whereby when said bars are folded with the tube sections one of said bars will be above the plane of the tube hinge.

7. An elevator and stacker, comprising a supporting frame, a stacker frame pivotally connected to said supporting frame, a shaft mounted on the stacker frame, a stacker tube pivoted to said stacker frame at an angle to the pivotal connection of the stacker frame to the supporting frame, and having a portion curved substantially concentric with relation to the pivotal connection of said tube a trough having a curved portion partly overlapped by the curved portion of said stacker tube, and reciprocating bars provided with means for engaging material within the stacker tube operated by said shaft.

8. An elevator and stacker, comprising a supporting frame, a stacker frame pivotally connected to said supporting frame, a cranked shaft mounted on the stacker frame, a stacker tube pivoted to said stacker frame at an angle to the pivotal connection of the stacker frame to the supporting frame and having a portion curved substantially concentric with relation to the pivotal connection of said tube, a trough having a curved portion partly overlapped by the curved portion of said stacker tube, and reciprocating bars provided with means for engaging material within the stacker tube operated by said cranked shaft.

9. An elevator and stacker, comprising a supporting frame, a stacker frame pivotally connected to said supporting frame, a shaft mounted on the stacker frame, a stacker tube pivoted to said stacker frame at an angle to the pivotal connection of the stacker frame to the supporting frame, a trough partly overlapped by said stacker tube, oscillating bars provided with means for engaging material within the stacker tube operated by said shaft, and reciprocating bars provided with means for engaging material

within the stacker tube connected to said oscillating bars.

10. An elevator and stacker, comprising a supporting frame, a rectangular stacker frame pivotally connected to said supporting frame, a cranked shaft mounted on the stacker frame, a trough connected to said rectangular stacker frame, a stacker tube pivoted to said stacker frame at an angle 10 to the pivotal connection of the rectangular frame to the supporting frame and a portion of said stacker tube extending below the trough, an oscillating bar provided with means for engaging material within the 15 stacker tube operated by said cranked shaft, and a reciprocating bar provided with means for engaging material within the stacker connected to said oscillating bar.

11. An elevator and stacker, comprising a supporting frame, a rectangular stacker frame pivotally connected to said supporting frame, a cranked shaft mounted on the stacker frame, a trough connected to said rectangular stacker frame, a stacker tube pivoted to said stacker frame concentrically 25 to the cranked shaft and at an angle to the pivotal connection of the rectangular frame to the supporting frame and a portion of said stacker tube extending below the trough, an oscillating bar provided with means for engaging material within the stacker tube operated by said cranked shaft, and a reciprocating bar provided with means for engaging material within the 30 stacker connected to said oscillating bars.

12. An elevator and stacker, comprising a supporting frame, a rectangular stacker frame pivotally connected to said supporting frame, a cranked shaft mounted on the stacker frame, a trough connected to said rectangular stacker frame, a stacker tube formed of two sections hinged together and pivoted to said stacker frame at an angle 40 to the pivotal connection of the rectangular frame to the supporting frame and a portion of said stacker tube extending below the trough, an oscillating bar provided with means for engaging material within the stacker tube operated by said cranked shaft, a guiding bars connected to said stacker tube, a sliding and pivotal means connecting the oscillating bar to the guiding bars, a reciprocating bar provided with means for engaging material within the stacker tube, 45 and a pivotal connection between the two bars whereby said bars may be folded with the tube sections.

13. An elevator and stacker, comprising a supporting frame, a rectangular stacker frame pivotally connected to said supporting frame, a cranked shaft mounted on the stacker frame, a trough connected to said rectangular stacker frame, a stacker tube formed of two sections hinged together and pivoted to said stacker frame at an angle 50 to the pivotal connection of the rectangular frame to the supporting frame and a portion of said stacker tube extending below the trough, an oscillating bar provided with means for engaging material within the stacker tube, a reciprocating bar provided with means for engaging material within the stacker connected to said oscillating bar.

to the pivotal connection of the rectangular frame to the supporting frame and a portion of said stacker tube extending below the trough, an oscillating bar provided with means for engaging material within the 70 stacker tube operated by said cranked shaft, guiding bars connected to said stacker tube, a sliding and pivotal means connecting the oscillating bar to the guiding bars, a reciprocating bar provided with means for engaging material within the stacker tube, means for supporting one portion of the reciprocating bar and permitting its reciprocation, and a pivotal connection between the two bars whereby said bars may be folded 75 with the tube sections.

14. An elevator and stacker, comprising a supporting frame, a stacker frame pivotally connected to said supporting frame, a shaft mounted on the stacker frame, a stacker tube pivoted to said stacker frame at an angle 80 to the pivotal connection of the stacker frame to the supporting frame, material moving means constructed to move material within the stacker tube operated by said shaft, a short shaft mounted on the supporting frame and provided with power transmission means, a short shaft mounted on the stacker frame, a universal coupling connecting the ends of the short shafts together, and power transmission means between the short shaft mounted on the stacker frame and the other shaft also mounted on said frame.

15. An elevator and stacker, comprising a supporting frame, a stacker frame pivotally connected to said supporting frame, a cranked shaft mounted on the stacker frame, a stacker tube pivoted to said stacker frame at an angle 90 to the pivotal connection of the stacker frame to the supporting frame, material moving means constructed to move material within the stacker tube operated by said cranked shaft, a short shaft mounted on the supporting frame and provided with power transmission means, a short shaft mounted on the stacker frame, a universal coupling positioned in alinement with one of the pivotal connections and connecting the ends of the short shafts together, and power transmission means between the short shaft mounted on the stacker frame and the cranked shaft also mounted on said frame.

16. An elevator and stacker, comprising a supporting frame, a stacker frame pivotally connected to said supporting frame, a cranked shaft mounted on the stacker frame, a stacker tube pivoted to said stacker frame at an angle 100 to the pivotal connection of the stacker frame to the supporting frame, means for adjusting the angle of the stacker tube, a guide for said adjusting means positioned in alinement with the pivotal connection of the stacker frame to the sup- 105 110 115 120 125 130

porting frame, material moving means constructed to move material within the stacker tube operated by said cranked shaft, a short shaft mounted on the supporting frame and provided with power transmission means, a short shaft mounted on the stacker frame, a universal coupling positioned in alinement with one of the pivotal connections and connecting the ends of the short shafts together, and power transmission means between the short shaft mounted on the stacker frame and the other shaft also mounted on said frame.

17. An elevator and stacker, comprising a supporting frame, a stacker frame pivotally connected to said supporting frame, a cranked shaft mounted on the stacker frame, a trough connected to said stacker frame, a stacker tube pivoted to said stacker frame at an angle to the pivotal connection of the stacker frame to the supporting frame and a portion of said stacker tube extending below the trough, means for adjusting the angle of the stacker tube, a guide for said adjusting means positioned in alinement with the pivotal connection of the stacker frame to the supporting frame, material moving means constructed to move material within the stacker tube operated by said cranked shaft, a short shaft mounted on the supporting frame and provided with power transmission means, a short shaft mounted on the stacker frame, a universal coupling positioned in alinement with one of the pivotal connections and connecting the ends of the short shafts together, and power transmission means between the short shaft mounted on the stacker frame and the cranked shaft also mounted on said frame.

18. An elevator and stacker, comprising a supporting frame, a stacker frame pivotally connected to said supporting frame, a cranked shaft mounted on the stacker frame, a stacker tube pivoted to said stacker frame at an angle to the pivotal connection of the stacker frame to the supporting frame, means for adjusting the angle of the stacker tube, a guide for said adjusting means positioned in alinement with the pivotal connection of the stacker frame to the supporting frame, an oscillating bar provided with engaging fingers for engaging material within the stacker tube operated by said cranked shaft, a reciprocating bar provided with engaging fingers for engaging material within the stacker tube pivotally connected to said oscillating bar, a short shaft mounted on the supporting frame and provided with power transmission means, a short shaft mounted on the stacker frame, a universal coupling positioned in alinement with one of the pivotal connections and connecting the ends of the short shafts together, and power transmission means between the short shaft mounted on the stacker frame and the cranked shaft also mounted on said frame.

19. An elevator and stacker, comprising a supporting frame, a stacker frame pivotally connected to said supporting frame, a cranked shaft mounted on the stacker frame, a curved trough connected to said stacker frame, a stacker tube formed of two sections hinged together pivoted to said stacker frame at an angle to the pivotal connection of the stacker frame to the supporting frame and a portion of the said tube extending below the curved trough, an oscillating bar provided with engaging fingers for engaging material within the stacker tube operated by said cranked shaft, a reciprocating bar provided with swinging engaging fingers for engaging material within the stacker tube pivotally connected to said oscillating bar, a short shaft mounted on the supporting frame and provided with power transmission means, a short shaft mounted on the stacker frame, a universal coupling positioned in alinement with one of the pivotal connections and connecting the ends of the short shafts together, and power transmission means between the short shaft mounted on the stacker frame and the cranked shaft also mounted on said frame.

20. An elevator and stacker, comprising a supporting frame, a stacker frame pivotally connected to said supporting frame, a cranked shaft mounted on the stacker frame, a curved trough connected to said stacker frame, a stacker tube formed of two sections hinged together pivoted to said stacker frame at an angle to the pivotal connection of the stacker frame to the supporting frame and a portion of the said tube extending below the curved trough, an oscillating bar provided with engaging fingers for engaging material within the stacker tube operated by said cranked shaft, a reciprocating bar provided with swinging engaging fingers for engaging material within the stacker tube pivotally connected to said oscillating bar, a short shaft mounted on the supporting frame and provided with power transmission means, a short shaft mounted on the stacker frame, a universal coupling positioned in alinement with one of the pivotal connections and connecting the ends of the short shafts together, and power transmission means between the short shaft mounted on the stacker frame and the cranked shaft also mounted on said frame.

21. A swiveled frame for an elevator and stacker, comprising a supporting frame, a stacker frame pivotally connected to said supporting frame, a curved trough connect-

125

ed to the stacker frame, and a stacker tube pivoted to the stacker frame at an angle to the pivotal connection of the stacker frame to the supporting frame and provided with 5 a portion substantially concentric with the curve of the trough.

22. A swiveled frame for an elevator and stacker, comprising a supporting frame, a stacker frame pivotally connected to said 10 supporting frame, a stacker tube pivoted to the stacker frame at an angle to the pivotal connection of the stacker tube to the sup-

porting frame and provided with a portion curved concentrically to its pivotal connection, and a trough connected to said stacker frame and having a portion substantially concentric to the curve of the stacker tube. 15

In testimony whereof, I affix my signature, in presence of two witnesses.

AUGUST ROSENTHAL.
